Attorney.

UNITED STATES PATENT OFFICE.

HENRY H. GOVE, OF BIDDEFORD, MAINE, ASSIGNOR OF ONE-HALF TO JOHN F. DEAN, OF BIDDEFORD, MAINE.

VALVE CONSTRUCTION FOR INTERNAL-COMBUSTION ENGINES.

1,303,654.

Specification of Letters Patent. Patented May 13, 1919.

Application filed May 15, 1916, Serial No. 97,458. Renewed November 9, 1918. Serial No. 261,935.

To all whom it may concern:

Be it known that I, HENRY H. GOVE, a citizen of the United States, and resident of Biddeford, in the county of York and State of Maine, have invented an Improvement 5 of Valve Constructions for Internal-Combustion Engines, of which the following description, in connection with the accompanying drawings, is a specification, like 10 letters on the drawings representing like parts.

My present invention is an improvement in internal combustion engines, particularly in the valve construction for such engines, 15 and the object of the invention is to simplify and improve rotary valves for such engines. In my development of the rotary valve construction, as shown in my copending applications, Ser. Nos. 830,906, filed April 20 10, 1914, and 20,600, filed April 12, 1915, I have illustrated very simple and efficient forms of rotary valve and valve casing, comprising means to control both the supply and exhaust to one or more cylinders of 25 an internal combustion engine, to provide for independent expansion and contraction of different valve sections, and to provide novel forms of compression rings and carbon shearing devices. In the present invention I have still further developed means 30 to insure the smooth and even running of this type of rotary valve mechanism. Important features consist in the improved arrangement and packing for the exhaust 35 conduit through the valve, the supply manifold, connections of the adjacent valve sections, and arrangement of a plurality of rings coöperating with the carbon shearing and compression member.

Other features of the invention, details 40 of construction and novel combinations of parts will be hereinafter more fully pointed out and claimed.

Referring to the drawings illustrating a 45 preferred embodiment of the invention,

Figure 1 is a cross sectional view through a fragmentary portion of a four cylinder internal combustion engine;

Fig. 2 is a view of one of the rotary valve 50 sections;

Fig. 3 is a cross sectional view along the line 3-3 of Fig. 1;

Fig. 4 is a view in perspective of my im-

proved compression and carbon shearing device; and

Fig. 5 is an enlarged cross sectional view of a fragmentary portion of the bearing between the rotary valve and its casing.

Fig. 6 is a side view of the valve showing a modification of spiral oiling groove and 60 compression ring therein.

I have illustrated in diagrammatic form the essential parts only of the top portions of the cylinders in a motor with an arrangement for the valve and casing formed across 65 the ends of said cylinders, although it will be understood that such valve may be arranged at the side, and may be employed for an internal combustion engine having only two cylinders, or even one. An engine 70 casing 1 is shown with a plurality of cylinders 2, 3, 4 and 5 having provision for the usual water jacket 6, said cylinders having ports 7, 8, 9 and 10 respectively, opening into the rotary valve seat 12 formed in 75 the casing 13 extending across all the cylinders and adapted to receive the rotary valve, the seat 12 being of suitable diameter for the valve to fit therein. It will be understood that the valve casing 13 may also contain 80 continuations for the circulation of water in the water jacket 15, as is usual, and may be formed as an integral casting with the engine casting 1, or be formed separately and bolted or otherwise secured to the head of 85 said casting 1, both these forms being illustrated in my two prior applications above mentioned.

I prefer to form the rotary valve in sections, thus allowing each section to expand 90 and contract freely and yet uniting all the sections for uniformity in operation and preferably having one section control two adjacent cylinders. To this end I form the valve sections 16 and 17, the former to control the supply and exhaust for the cylinders 4 and 5 and the latter for the cylinders 2 and 3, connecting said sections by a dovetailed mortise joint, comprising tongue members 18 (one only being shown in the 100 drawing) on the section 16 and corresponding sockets 19 on the adjacent end of the valve sections 17. I prefer to have two or more of such tongues and sockets so arranged around the periphery of the abutting 105 valve sections 16 and 17 as to insure a proper

assembling of the valve sections and also so that the same will permit ready removal. If the section 16, for example, is drawn out endwise from the valve casing, the section 5 17 will, of course, be brought with it and only one end of the valve casing need be removed. To facilitate this operation and also to provide simple and convenient construction, I form the valve seat 12 entirely 10 open through the casing, bolting a cover and bracket 20 at one end adapted to conceal and protect the gear 21 which is removably affixed to the end of the adjacent valve section 16 and also to further provide a bearing 15 for the gear 22 and shaft 23 imparting rotation to the valve from the crankshaft or any suitable source of power in a similar manner to that explained in my said co-pending application, Ser. No. 20,600. The 20 opposite end of the valve seat is closed and protected by a cover 24 bolted around its edge to the casing, further providing a ball or roller thrust bearing for the rotary valve. The valve casing is adapted to receive a 25 supply manifold 25 which opens into annular enlargements or recesses 26, 27 and 28 at the middle and adjacent each end of the casing herein shown, the middle recess 27 giving a supply of fuel where the 30 abutting ends of the valve sections 16 and 17 are joined by the mortise members above described, said sections being spaced apart to permit of an intake of fuel from the annular passage 27. A flow of fuel into each 35 open end 29 and 30 of said sections is thus permitted and a supply to the respective ports 8 and 9 at proper times is given. The closed end of the valve 16 is provided with a plurality of ports 31 in position to pick up 40 the fuel from the annular passage 28 and supply same through the open section 32 of the valve sections 16 to the port 10 of the cylinder 5 at appropriate times to the supply port 33 in the valve. A similar construction 45 comprising the ports 34 in the valve section 17 adjacent the supply passage 26 is arranged to admit the supply into the port 35 of said valve section for admission through the port 36 to the cylinder 2. 50 Each section 16 and 17 is similarly constructed, having exhaust conduits in the form of sleeves 37 and 38 respectively, and openings 39 and 40 through exhaust ports 41 and 42 respectively, as shown in Fig. 1. 55 The conduit 37 has one opening 42 in position to conduct the exhaust from the cylinder 5 and the other port 43 to take the exhaust from the cylinder 4. The conduit 38 has corresponding ports 44 and 45 for its 60 cylinders 2 and 3. These exhaust ports may be arranged either at right angles or any other, for proper timing of the valve and engine cylinders, as well as are the intake ports therefor, the arrangement herein illustrated being on the ratio of one revolution 65

of the rotary valve to two revolutions of the crank shaft. The flow of the heated exhaust through the conduits 37 and 38 and the supply of cool fuel tend to equalize temperatures, each valve section being independent 70 of the adjacent section in this respect. I prefer to arrange an asbestos packing 46 around the exhaust conduits, retaining same with washers 47 where necessary, and thus entirely shutting off the supply portions of 75 each rotary valve section from each other. This arrangement also prevents undue heat and distortion being communicated from the exhaust conduits 37 and 38 to the respective outer portions of the rotary valves where 80 said valves bear upon the face of the valve seat 12. As a still further preventive against undue expansion between the outer bearing surface of the rotary valve sections and the seat 12 in the casing, I prefer to 85 recess both the seat 12 and the adjacent portions of the rotary valve, at similar points 48 and 49 respectively (see Fig. 1), thus giving a wide port opening and also insuring against the valve binding or sticking in 90 its rotative movement.

The exhaust ports 41 and 42 I prefer to form with enlarged recesses at the opening of said ports, as indicated at 50, Fig. 3, thus permitting the flow of the exhaust from the 95 adjacent cylinders controlled by an exhaust conduit 37 in the valve section 16, for example, to be almost continuous through successive exhausts of the adjacent cylinders 4 and 5. This construction gives great freedom for the escape of the exhaust gases and insures an easy, rapid and complete scavenging of the cylinders of substantially all the products of combustion prior to the intake. 105

In my prior applications I have illustrated and explained my novel form of compression and carbon shearing devices, consisting in a pair of expansible compression ringlike members 51 and 52 connected by a cross bar 53 as illustrated in Fig. 4. Said rings and cross bar fit within appropriate circumferential and longitudinal grooves 54, 55 and 56 respectively in the outer surface of the rotary valve 16 as illustrated in Fig. 5. I 110 have discovered that this combined compression and carbon shearing device operates much more satisfactorily and thoroughly if the cross bar 53 is adjacent the cut 57 in each ring, thus preventing cutting of the rings, 115 and providing better spring tension on the cross bar and less liability to break or injure the device than when the cut is diametrically opposite the cross bar 53 especially in assembling. Furthermore, as this valve rotates in the direction of the arrow in Fig. 4, an edge of the cross bar is presented uppermost. This feature is distinctly novel and valuable and adds materially to the long life of the valve. I also find it de- 120 125 130

sirable to form the peripheral recesses 54 and 55 of sufficient width to receive compression rings 58 and 59 respectively, in addition to the ringlike members 51 and 57. The 5 combination of such support and independent compression rings, together with the rings and cross bar 53, proves to be advantageous in actual practice. My compression and carbon shearing device is prefer- 10 ably arranged about the rotary valve at each engine port and hence at each of the exhaust ports 42 and 43 in a conduit 37 and 44 and 45 in the conduit 38. In Fig. 3 I have illustrated the passage 60 to receive the 15 spark plug, which is provided in each cylinder, as, of course, will be understood.

As illustrated in Fig. 6, I have shown a novel form of combined compression ring, carbon shearing, and oiling device, which 20 may be utilized as a modification of the carbon shearing and compression member illustrated in Fig. 4. Each section of my rotary valve may be provided with a spiral groove 65, cut in the outer surface of the 25 valve section and in a spiral to clear the several ports 39, 33, 43, in which groove is a spiral expansible ring 66. Such groove 65 and ring 66 may extend throughout the entire length of the rotary valve section and 30 while it may be employed in combination with the compression device of Fig. 4, the same may also be used independently. So far as I am informed, it is a distinct novelty in this art to provide, in a rotary valve for 35 internal combustion engines, a spiral groove and an expansible compression ring fitted in said groove; also to provide such a groove and ring which will be so arranged and constructed as to constitute an effective com- 40 pression device between the ports of the valve; and furthermore to so arrange such groove and ring that the latter will act as an efficient carbon shearing member. In addition to these features, the groove and 45 spiral ring may also be advantageously utilized to act as an oil distributing device.

My improved rotary valve construction, as herein explained, eliminates the friction of the valve turning in its seat 12 by having 50 reduced portions 48 and 49, simplifying the machining of both valve and seat, providing free expansion for each section, and facilitating assembling and removal of the sections, as well as greatly simplifying the 55 manufacture for both engine and valve casing. I am enabled to utilize a single port in each cylinder for both supply and exhaust and a single exhaust port through the casing for each pair of cylinders. The 60 asbestos packing largely prevents undue heating and such reduction in the continuous heating and cooling of the valve sections insures even running as well as strength to the valve and eliminates the danger of the 65 exhaust conduits separating from the valve sections at the ports, thus preventing leakage, or the like. The arrangement of at least a pair of cylinders and the exhaust conduit controlling such pair with the widened openings 50, producing a substantially continuous flow of exhaust gases and acts largely as a muffler for the engine. 70

My invention is further described in the form of claims as follows:

1. An internal combustion engine having 75 a plurality of cylinders, a hollow rotary valve extending adjacent at least two of said cylinders, a casing therefor in which said valve is adapted to rotate, means to rotate the valve in timed relation with the 80 engine cylinders, said valve having an exhaust conduit extending longitudinally therethrough and adapted to register, at either end, with the exhaust of a cylinder, a central outlet from said exhaust conduit 85 substantially midway of its length, heat insulating means surrounding a portion of the exhaust conduit adjacent the outlet and separating the hollow valve into a plurality of fuel supply portions, and supply ports from 90 each of said fuel supply portions into the adjacent engine cylinders.
2. An internal combustion engine having 95 a plurality of cylinders, a hollow rotary valve extending adjacent at least two of said cylinders, a casing therefor, in which said valve is adapted to rotate, means to rotate the valve in timed relation with the engine cylinders, said valve having an exhaust conduit 100 extending longitudinally therethrough and adapted to register, at either end, with the exhaust of a cylinder, a central outlet from said exhaust conduit substantially midway of its length, heat insulating means surrounding a portion of the exhaust conduit adjacent the outlet and separating the hollow valve into a plurality of fuel supply portions, fuel supply openings from 105 each end of said valve into said supply portions, a port from said fuel supply portion 110 adapted to register with the single port in the adjacent cylinder in timed relation with the registering of the exhaust port therewith, an enlarged circumferential recess in the valve casing adjacent the central exhaust port and compression members carried by the rotary valve at either side of said recess.
3. The combination with an internal combustion engine and its cylinders of a rotary 115 valve and a casing therefor, exhaust ports therethrough, and a compression device adjacent an exhaust port consisting in a plurality of inherently expansible split rings rigidly united by a single squared cross-bar 120 joining said rings at the split portion of each ring, the free length of the expansible ring members causing an edge of said cross-bar to be normally forced outwardly against 125 the inner walls of said valve casing and the 130

- outer edge will constitute a carbon shearing edge to prevent the formation, and remove as formed, the carbon adjacent said exhaust port.
- 5 4. An internal combustion engine having a plurality of cylinders, a hollow rotary valve adjacent two or more of said cylinders, a casing for said valve, means to rotate the valve in timed relation with the engine, 10 said rotary valve being adapted to receive, conduct and control the supply and exhaust from said cylinders, and having an exhaust pipe extending longitudinally within the
- hollow valve with means adjacent either end to receive the exhaust from a cylinder, together with an outlet from said exhaust pipe through said valve dividing the supply portion substantially midway of its length. 15
- In testimony whereof, I have signed my name to this specification, in the presence 20 of two subscribing witnesses.

HENRY H. GOVE.
